UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

BUFFER FOR AUTOMOBILE DOORS.

Application filed February 19, 1921. Serial No. 446,376.

To all whom it may concern:

Be it known that I, JOSEPH LEDWINKA, residing at Philadelphia, county of Philadelphia, Pennsylvania, have invented certain new and useful Improvements in Buffers for Automobile Doors, of which I declare the following to be a full, clear, and exact description.

My invention relates to improvements in buffers for automobile doors. This invention is an improvement upon the invention relating to anti-rattling devices or buffers for automobile doors described and claimed broadly in my co-pending application, Serial No. 433,379, filed December 27th, 1920, automobile bodies and the method of making same.

One of the principal objects of my invention is to provide an efficient and simple device for preventing the rattling of automobile doors, which may be manufactured and assembled at a-comparatively low cost.

Another object of my invention is to provide an anti-rattling device for automobile doors in which the buffer member, which may be made of rubber or other resilient material, is of uniform cross-section throughout its length so that the individual buffer members can be made by cutting a long strip of rubber or similar resilient material into the desired lengths, thus simplifying the manufacture of the buffer members and reducing their cost.

Another object of my invention is to provide a buffer member of rubber, or similar resilient material, having a longitudinally extending rib with laterally extending shoulders which may be compressed, in order to pass the rib through the opening in which the buffer member is mounted, and then allowed to expand laterally behind the walls at the side edges of said opening, so as to anchor the buffer member in place.

Further objects, and objects relating to economics of material and details of construction, will definitely appear from the detailed description to follow. I accomplish the objects of my invention, in one instance, by the devices and means described in the following specification. My invention is clearly defined and pointed out in the appended claims. A structure, constituting a preferred embodiment of my invention, is illustrated in the accompanying drawings,

forming a part of this specification, in which:

Fig. I is a fragmentary side view of an automobile body showing a door post equipped with buffers in accordance with my invention.

Fig. II is an enlarged, transverse, sectional view, taken substantially on the line II—II of Fig. I.

Fig. III is a detail, sectional view, taken on the line III—III of Fig. II.

Fig. IV is a longitudinal, sectional view through the buffer member, taken on the line IV—IV of Fig. II.

Fig. V is a view of the buffer member in side elevation, taken along a line parallel to the line IV—IV of Fig. II.

Fig. VI is a perspective view of an embodiment of my invention for use in connection with a wooden door post, and

Fig. VII is a sectional view taken on line VII—VII of Fig. VI.

Similar reference numerals refer to similar parts throughout the several views and the sectional views are taken looking in the direction of the little arrows at the ends of the section lines.

In general, I carry out the objects of my invention by providing a buffer member having a rib extending longitudinally thereof, said rib having portions extending laterally so that the rib flares outwardly from its base, that is, from the points where it is connected with the body portion of the buffer member. I have found it very desirable to make the body portion of the buffer cylindrical and, in such case, it is very desirable to form the rib in the shape of a radially-extending sector-shaped portion on the cylindrical body portion. This form is desirable because of the simplicity of manufacture, but I am not to be restricted to this particular form as will appear from the appended claims. I also find it very desirable to provide the body portion of the buffer member with shoulders which extend radially from the body portion of the buffer and serve to anchor the buffer member in place. The buffer member is preferably made of rubber, or rubber composition, but may be made of other material having the desired resilient qualities.

These buffer members are to be mounted in a door post so as to engage the edge of the door and absorb its vibrations. I have found it very desirable to mount the buffer member

in place by providing a buffer chamber in the door post with an opening leading to it. The radially projecting shoulders of the rib on the buffer member are compressed, 5 so that the rib is forced through the opening, and these shoulders are then allowed to expand behind the walls of the chamber at the sides of the opening so as to anchor the buffer member in place. The back 10 wall of the chamber may engage the anchoring rib on the buffer member and act as a retaining plate or member. I have found that the best results are attained by providing the chamber and the opening in the angular portion of the door post, which acts 15 as a stop for the edge of the door. When arranged in this way, the buffer member absorbs the vibrations longitudinally of the body, as well as transversely. In a metal 20 body construction, the chamber for the buffer member may be formed by applying a retaining plate or member to the inner surface of the metal door post, behind an opening formed in the door post for the buffer 25 member. It is obvious that this buffer chamber may be either formed in the door post or formed in a separate member which is applied to and fastened in the proper position in the door post.

30 In the accompanying drawings, in which I have illustrated a construction which constitutes one embodiment of my invention, I have shown an automobile body, 10, having the customary doors 11. I have shown a pair 35 of buffer members, 22, mounted in the door post indicated at 13, in Fig. I. In the construction illustrated, the door post, 13, has an inner flange, 12, and an outer flange or shoulder, 14, which may lie substantially 40 parallel to the flange, 12, and at right angles to the face of the door post, 13. The flange, 15, may extend at right angles to the shoulder, 14, and parallel to the face of the door post, 13. The side panel, 16, of the automobile body shell, may have its flange, 17, 45 secured to the flange, 15. In this particular body construction, the door post is formed of a metal bar or stamping having the cross section shown. The buffer chamber may be 50 formed by a plate which has a curved central portion, 19, with upper and lower angular flanges, 20 and 21, which lie against and may be secured, by welding, to the inner surfaces of the portions, 13 and 14, of the door 55 posts. An opening, 18, is formed in the door post, partly in the face, 13, and partly in the shoulder, 14, so that the opening is formed in the angular portion between these two parts. The retaining member, 19, may be 60 fastened to the inner surfaces of the door post behind the opening, 18, so that it presents its concave face towards said opening. The buffer member is formed of rubber or other resilient material and may comprise 65 the cylindrical body portion, 22, and the ra-

dially extending sector or rib, 23. This rib extends longitudinally of the buffer member and has, at each side, the shoulders, 24, which may extend radially of the buffer member. The side edges of the concave face of the 70 plate, 19, abut the surfaces, 13 and 14, respectively, a short distance from the sides of the opening, 18, as shown in Fig. II. The buffer member is inserted in place by engaging one of the shoulders, 24, of the sector-shaped rib, 75 23, behind one of the walls at the side of the opening, 18, and forcing the buffer member inwardly so as to compress the opposite shoulder, 24, until it has passed through the opening, 18, after which it may expand 80 freely and seat itself behind the wall at the opposite side of said opening, 18. In this position, the buffer member is anchored in place and the curved surface of the sector-shaped rib, 23, will seat itself on the concave 85 face of the retaining member, 19.

In Figs. VI and VII, I have shown an embodiment of my invention which is particularly adapted for use in connection with wooden door posts such as are usual in composite automobile bodies. In these views the wooden door post, 25, is indicated in dotted lines, being rabbeted at 26' to receive the buffer. An angle plate, 27, may be fastened on the corner of the door post, 25, in any 90 suitable manner and has an opening, 28, formed in the angle of the plate in the same way as the opening, 18, shown in the door post of Fig. I. A buffer retaining member, 19, may be fastened to the back faces of the 95 angle plate, 27, so as to form a buffer chamber, and a buffer member, 22, of rubber or resilient material is anchored in the chamber in the same way as described with reference to the preceding construction.

When anchored in this position, the main cylindrical body portion of the buffer member projects from the angular portion of the door post, as shown in Fig. II. The door, 11, has a shoulder, 25, which, in the closed 100 position of the door, is parallel to the face, 13, of the door post, and an edge flange, 26, which, in the closed position of the door, is parallel to the shoulder or stop flange, 14, of the door post. It will appear that, when the 105 door is brought to the closed position, a part of the buffer member, 22, will be compressed against the shoulder, 25, of the door and another part of the buffer member will be compressed against the edge flange, 26. The 110 result is that this buffer will be effective to absorb the vibrations longitudinally of the body, which would otherwise cause a rattle between the door and the door post, and the vibrations transversely of the body, which 115 would otherwise cause a rattle between the flange of the door and the stop flange of the door post. From the foregoing it will appear that this buffer construction, although 120 it is very simple and easily manufactured, 125 130

is effective to absorb practically all the vibrations which would otherwise cause a rattle between the door and the door post. It will be observed that the buffer member, 22, is of uniform cross-section throughout its length. This is a feature of considerable importance, because the buffer members may be moulded in a long strip which is afterward cut up into the required lengths for the individual buffer members. This is a decided improvement over the construction shown in my co-pending application, which I have referred to, in which the buffer members have to be moulded or formed individually. As a result, the construction which I have shown here, may be produced at a lower cost than the construction in my prior application.

I am aware that the particular embodiment of my invention, which I have shown and described, may be varied considerably without departing from the spirit of my invention, and, therefore, I claim my invention broadly, as well as specifically, as indicated by the appended claims.

Having thus described my invention, what I claim as new and desire to secure by Letters Patent is:

1. In an automobile body, the combination 30 of a door post having a buffer chamber therein and an opening communicating with said chamber, and a buffer member of resilient material positioned in said opening and having a longitudinally extending portion seated in said chamber and engaging behind shoulders at the sides of said opening.

2. In an automobile body, the combination 40 of a door post having a buffer chamber therein and an opening communicating with said chamber and a buffer member of resilient material positioned in said opening and having a cylindrical body of greater diameter than the width of said opening and a radially projecting rib of greater width than said opening, the latter being seated in said chamber and the former extending outside of said chamber.

3. In an automobile body, the combination 50 of a door post having a buffer chamber therein and an opening communicating with said chamber, and a buffer member of resilient material having a body portion positioned in said opening and a pair of laterally projecting shoulders seated behind the chamber walls at the sides of said openings.

4. In an automobile body, the combination 60 of a door post having a buffer chamber therein and an opening communicating with said chamber, and a buffer member of resilient material having a cylindrical body portion positioned in said opening and a radially projecting sector-shaped portion seated in said chamber.

5. In an automobile body, the combination

of a metal door post having a part of angular cross-section forming a door stop, said portion of angular cross-section having an opening formed therein, a buffer retaining member secured to the inner surface of said door post behind said opening, and a buffer member of resilient material positioned in said opening and having a longitudinally extending rib seated against said retaining member and anchoring the buffer member in the door post. 70

6. In an automobile body, the combination of a metal door post having a part of angular cross-section forming a door stop, said portion of angular cross-section having an opening formed therein, a buffer retaining member secured to the inner surface of said door post behind said opening, and a buffer member of resilient material positioned in said opening and having a cylindrical 80 body portion of greater diameter than the width of said opening and a radially extending rib of greater width than said opening, the latter being seated against said retaining member and the former extending 90 outside of said door post.

7. In an automobile body, the combination of a metal door post having a part of angular cross-section forming a door stop, said portion of angular cross-section having an opening formed therein, a buffer retaining member secured to the inner surface of said door post behind said opening, and a buffer member of resilient material having a body portion positioned in said opening and a pair 95 of laterally extending shoulders seated behind the portions of said door posts at the sides of said opening.

8. In an automobile body, the combination 105 of a metal door post having a part of angular cross-section forming a door stop, said portion of angular cross-section having an opening formed therein, a buffer retaining plate curved transversely and fastened to the inner surface of said door post behind 110 said opening, and a buffer member of resilient material having a cylindrical body portion positioned in said opening and a radially-extending sector-shaped portion seated against said curved retaining member. 115

9. A buffer member for automobile doors comprising a cylindrical member of resilient material having a laterally projecting rib extending longitudinally thereof.

10. A buffer member for automobile doors, 120 comprising a cylindrical member of resilient material having a pair of radially projecting shoulders extending longitudinally thereof.

11. A buffer member for automobile doors, comprising a member formed of resilient 125 material and having a pair of longitudinally extending grooves in the opposite sides thereof.

12. A buffer member for automobile doors, comprising a cylindrical member of resilient 130

material having a radially projecting sector-shaped member extending longitudinally thereof.

13. In a buffer structure for automobile doors, a door post having a recess or chamber, and a buffer member of resilient material, a portion of the buffer member extending into the recess or chamber of the door post and having a shoulder to engage behind 10 the adjacent edge of the wall of the recess or chamber.

14. In a buffer structure for automobile doors, a door post having a recess or chamber, and a buffer member of resilient material, a portion of the buffer member extending into the recess or chamber of the door post and engaging behind the adjacent edges 15 of the wall of the recess or chamber.

15. In a buffer structure for automobile

doors, a door post having a portion of an- 20 gular cross-section to form a door stop, said portion formed with an opening through the angle thereof, in combination with a buffer member of resilient material, a portion of 25 said buffer member extending through said opening and engaging behind the adjacent edges of said opening.

16. A buffer structure for automobile doors including a member of angular cross- 30 section having an opening in the angle there- of, and a buffer member of resilient mate- rial positioned in said opening and having portions engaging behind the portions of 35 said member forming the side edges of said opening.

In testimony whereof, I affix my signature.

JOSEPH LEDWINKA.
